UNITED STATES PATENT OFFICE

168,500

PLATE OR SIMILAR ARTICLE

Violet M. Fellows, Ponca City, Okla., assignor to Fred G. Fellows, Ponca City, Okla.

Application June 11, 1952, Serial No. 20,126

Term of patent 14 years

(Cl. D44—15)

To all whom it may concern:

Be it known that I, Violet M. Fellows, a citizen of the United States, residing at Ponca City, in the county of Kay and State of Oklahoma, have invented a new, original, and ornamental Design for a Plate or Similar Article, of which the following is a specification, reference being had to the accompanying drawing, forming part thereof.

Figure 1 is a top plan view of a plate or similar article showing my new design, and

I claim:

The ornamental design for a plate or similar article, as shown.

VIOLET M. FELLOWS.
